UNITED STATES PATENT OFFICE

LEO J. GRUBMAN, OF BELLE HARBOR, LONG ISLAND, NEW YORK, ASSIGNOR TO MARGON CORPORATION, OF NEW YORK, N. Y., A CORPORATION OF NEW YORK

ARTIFICIAL EYE FOR DOLLS, MANIKINS, AND OTHER FIGURE TOYS

Application filed February 24, 1927. Serial No. 170,446.

This invention relates to artificial eyes for dolls, manikins and other figure toys, and has for its primary object and purpose to provide an eye structure which is of simple and substantial construction, and may be rapidly produced in large quantities at low manufacturing cost.

It is another and more particular object of the invention to provide an artificial eye structure embodying improved means whereby the eyelashes are permanently secured in attached relation and at a definite angle of projection with respect to the surface of the eye structure at the upper edge of the eye 15 pupil represented thereon.

In a preferred embodiment of the invention, I provide an inner shell of celluloid and an outer thin metallic shell closely enveloping the inner shell, and provided with an eye 20 shaped opening in its wall. A part of the wall of the inner shell conforming in shape with said opening is angularly projected outwardly through the opening and between said part of the inner shell and the upper edge of 25 the opening in the outer shell, the ends of the eyelash strands are positioned, said strand ends being embedded and adhesively held in the structure of the inner celluloid shell. The outer face of the projected section of the inner 30 shell wall is positioned in the same plane as the outer surface of the outer shell wall and the shoulder thus formed by said projected shell section at the upper edge of the opening in the outer shell determines the angular 35 projection of the eyelash strands from the outer surface of the eye structure.

It is also another object of the invention to provide simple and effective means whereby the inner and outer shells of the eye structure 40 may be securely interlocked or permanently connected with each other in assembled relation.

With the above and other objects in view, the invention consists in the improved artificial eye structure and in the form, proportion and relative arrangement of its several 45 parts as will be hereinafter more fully described, illustrated in the accompanying drawings, and subsequently incorporated in 50 the subjoined claims.

In the drawings, wherein I have illustrated several simple and practical embodiments of the invention, and in which similar reference characters designate corresponding parts throughout the several views,

Figure 1 is a vertical sectional view through an artificial eye constructed in accordance with one embodiment of the invention;

Fig. 2 is a bottom plan view thereof;

Fig. 3 is a view similar to Fig. 2 partly in section showing a slightly modified means for connecting the inner and outer shell members with each other, and

Fig. 4 is a vertical section similar to Fig. 1 illustrating a further modification of the 65 device.

Referring in detail to the drawings, and more particularly to Figs. 1 and 2 thereof, I preferably though not necessarily, form the inner shell member 5 of the eye structure 70 from celluloid or other thermo-plastic material which is drawn from a sheet of such material into the semi-spherical form illustrated in the drawings. At the appropriate location on the surface of the celluloid sheet 75 which forms the outer convex surface of the semi-spherical shell, the representation of the pupil of the human eye, indicated at 6 is printed, painted, or otherwise delineated.

The second primary element of the eye 80 structure consists of an outer shell 7 which is also drawn into semi-spherical form from a relatively thin sheet of metal. This outer shell is of such internal diameter as to snugly receive the inner shell 5, the wall of said outer 85 shell being longitudinally extended to a greater length than the wall of the inner shell from the curved portion thereof for a purpose which will hereinafter become apparent. The wall of the outer metal shell 7 90 at the proper location is provided with an elliptical or eye shaped opening 8 therethrough, which however, is of appreciably greater dimensions than the dimensions of the eye pupil represented on the surface of 95 the inner shell.

In a companion application for patent filed of even date herewith, I have fully described the manner in which the inner and outer shell members together with the eyelash 100

strands indicated at 9 are assembled and secured in relatively fixed relation to each other. For the purpose of this application, it will suffice to state that the ends of the lash strands 9 are positioned between the wall of the outer shell 5 at the upper edge of the opening 8 therein, and an angularly offset or projected section 10 of the wall of the inner celluloid shell 5 which substantially completely fills the opening 8 of the outer shell, said section 10 of the inner shell wall being thus outwardly offset for a distance equivalent to the thickness of the outer shell so that the outer surface of the inner shell wall section 10 and the outer surface of the outer shell 7 are positioned in the same circumferential plane. The ends of the eyelash strands 9 extend a short distance above the upper edge of the opening 8 and are embedded under heat and pressure in the thermo-plastic substance of the inner shell 5 so that these strand ends become intimately and inseparably incorporated in the wall structure of the inner shell. The outward projection of the section 10 of the inner shell wall provides an angular shoulder 11 at the upper edge of the opening 8 in the outer shell upon which the lash strands are clampingly held or confined by the wall 7, the inclination of said shoulder thus determining the angle of outward projection of the eyelash strands with respect to the part 10 of the inner shell above the eye pupil 6.

The outer surface of the outer shell 7 above the eyelashes 9 is properly painted to represent the upper eyelid, and the exposed surface of the part 10 of the inner eye shell surrounding the pupil 6 may also be properly painted or colored to realistically simulate the human eye. By attaching the eyelashes to the eye structure in this manner, to all external appearances, the lashes appear to grow out from the lower edge of the eyelid, no holding or securing means for the eyelash strands of any kind being visible. Also, after the outer exposed surfaces are properly painted, the lines of demarkation between the upper and lower edges of the opening in the outer shell 5 and the corresponding edges of the projected part 10 of the inner shell wall are not discernible.

Various means may be employed for permanently connecting or interlocking the inner and outer shells of the eye structure against relative movement from their nested or assembled positions. Thus, in Fig. 1 of the drawings, the longitudinal extension of the wall of the outer shell 7 which projects beyond the rear end edge of the wall of the inner shell 5, is turned or bent inwardly around said end edge of the inner shell wall and upon the inner face thereof as shown at 12, thus fixedly securing the two shells against relative longitudinal or axial movement. The part 10 of the inner shell projecting through

the opening in the wall of the outer shell constitutes a means which effectively locks the two shells against any possibility of relative rotation.

The opposite sides of the completed eye structure may then be provided with the aligned openings 13 of suitable size and shape to receive the shaft or axis of an eye setting whereby the two eyes may be properly assembled and mounted within the head of the doll or other figure.

In Fig. 3 of the drawings, I have illustrated another manner of permanently securing the inner and outer shells to each other whereby one of the operations above described may be eliminated, thus instead of making the outer shell of greater length and turning the rear end edge inwardly around the edge of the inner shell, in the formation of the shaft receiving openings 13 through the wall of the outer shell 7, the edges of the opening through this outer shell wall may be flanged inwardly as shown at 14 and in close contacting relation with the corresponding edges of the openings in the wall of the inner shell 5. In this case, it will be understood that the openings are provided through the wall of the inner shell during the separate manufacture thereof and accurately located with respect to the pupil 6 on the surface thereof prior to the final assemblage of the inner and outer shells with each other.

In Fig. 4 of the drawings, I have shown a further modification of the invention wherein the inner shell 5' as well as the outer shell 7' is produced from a thin sheet of metal. In this case, the wall of the inner shell in addition to having the outwardly projected section 10' positioned in the opening in the wall of the outer shell is further provided at the upper edge of the section 10' with a shallow depression 10^a in which the ends of the eyelash strands are adapted to be positioned. When the two shell members are forced together to their final nested positions under pressure of the assembling dies, the ends of the lash strands will be subjected to a heavy clamping pressure and they will be flattened out or transversely elongated between the wall of the depression 10^a and the inner face of the wall of the outer shell 7', thus obviating any possibility of the strand ends becoming detached from the eye structure. In this last described construction, either of the methods of permanently securing the two shell members in nested relation as above referred to may be adopted.

From the foregoing description considered in connection with the accompanying drawings, the construction and several advantages of my improved artificial eye structure will be clearly understood. It will be seen that by means of my invention, the use of adhesives or other additional fastening or securing means for the eyelashes is dispensed with,

and at the same time, I obtain a more natural or realistic appearance and a closer simulation of the human eye. It will also be apparent that the several parts of this new eye structure may be very rapidly assembled by my proposed method with the assurance of a definitely accurate relationship of the parts with respect to each other.

In the accompanying drawings, the thickness of the walls of the inner and outer shell members has been somewhat exaggerated for the purpose of clearness of the disclosure, which is particularly true of the inner celluloid shell 5. The wall of this shell need only be of such thickness that it may not be easily dented or collapsed so as to constitute a firm non-yielding support for the outer thin metal shell 7. It will also be understood that the artificial eye structure may be made in a great many different sizes for application to dolls or figures of varying size. Also, while I have referred to several simple and effective devices for fixedly interlocking or connecting the two shell members with each other, in so far as the means which I provide for the attachment of the eyelash strands to the eye structure is concerned, any other desired means might be utilized for permanently securing the shells in nested relation. Accordingly, it is to be understood that while I have herein disclosed several desirable and practical embodiments of the essential features of my present improvements, the device is also susceptible of incorporation in various other alternative structural forms, and I therefore, reserve the privilege of resorting to all such legitimate changes therein as may be fairly embodied within the spirit and scope of the appended claims.

I claim:

1. An artificial eye structure comprising an outer sheet metal shell having an eye shaped opening in its wall, an inner shell of thermo-plastic material having a section of its wall projected through and substantially closing said opening, the outer surfaces of the outer shell and the projected section of the wall of the inner shell being positioned in the same circumferential arc, and eyelash strands having one of their ends embedded in the structure of the inner shell wall and supported by the projected section of said wall in definite angularly projecting relation to the surface of the outer shell at one edge of the opening therein.

2. In an artificial eye structure, an outer sheet metal shell having an eye shaped opening in its wall, an inner shell of thermo-plastic material nested within said outer shell and having a section of its wall angularly offset and substantially closing the opening in the wall of the outer shell, eyelash strands having one of their ends positioned between the inner and outer shells at one edge of

the opening in the latter and embedded in the structure of the inner shell wall, said strands being sustained by the offset section of the inner shell wall in definite outwardly projecting angular relation with respect to the surface of the outer shell, and said outer shell having its rear edge turned inwardly around and upon the rear edge of the inner shell to permanently secure said shells in their nested position against relative movement.

3. An artificial eye comprising a semi-spherical shell having an eye pupil on its outer surface, a part concentrically curved in relation to the shell and superimposed thereon having a portion representing an eyelid, eyelash strands clamped at one of their ends between said part and the shell and projecting outwardly from the surface of the latter in appropriate relation to the eye pupil, and said superimposed part being further provided at opposite sides of the shell with portions interlocked with the shell wall to fixedly secure said part in attached relation to the shell.

4. An artificial eye comprising a semi-spherical shell having an eye pupil on its outer surface, a part concentrically curved in relation to the shell and superimposed thereon having a portion representing an eyelid, eyelash strands clamped at one of their ends between said part and the shell and projecting outwardly from the surface of the latter in appropriate relation to the eye pupil, said shell being provided in its wall at opposite sides thereof with axis receiving openings and said superimposed part having portions thereof projecting inwardly through said openings and engaged with the shell wall to fixedly secure said part in attached relation to the shell.

In testimony that I claim the foregoing as my invention, I have signed my name hereto.

LEO J. GRUBMAN.
